UNITED STATES PATENT OFFICE.

FRITZ KETTLER, OF MUNICH, GERMANY.

WRENCH.

1,391,898.

Specification of Letters Patent. Patented Sept. 27, 1921.

Application filed November 13, 1920. Serial No. 423,985.

To all whom it may concern:

Be it known that I, FRITZ KETTLER, a citizen of the Government of Germany, residing at Munich, Germany, have invented a new and useful Wrench, of which the following is a specification.

My invention consists of a wrench formed of a stationary jaw, a handed shank to which the latter is attached, a movable jaw mounted on said shank, a member in said shank to which said movable jaw is attached, said member having on its under side an inclined plane, and a lever mounted on said shank, said lever having its head portion adapted to engage with and ride on said inclined plane whereby when said lever is closed on the handle it advances the movable jaw toward the stationary jaw so that the article to which the wrench is applied is firmly gripped by the jaws.

It consists also of means in the shank and handle of the wrench for restoring the movable jaw to its normal position.

It consists also of various details of construction as will be hereinafter set forth.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a side elevation of a wrench embodying my invention;

Fig. 2 represents a partial side elevation and partial longitudinal section thereof;

Fig. 3 represents a longitudinal section on line 3—3, Fig. 2;

Fig. 4 represents a horizontal section on line 4—4 Fig. 2.

Fig. 5 represents a transverse section on line 5—5 Fig. 2.

Fig. 6 represents a top view of the wrench.

Fig. 7 represents a longitudinal section of a portion of the wrench in the closed position of the jaws.

Similar numerals of reference indicate corresponding parts in the figures.

Referring to the drawings.

1 designates the stationary jaw of the wrench, this being connected with the upper end of the shank 2 which latter is continued downwardly forming the handle 3.

4 designates the movable jaw of the wrench, the same being connected with the yoke 5, the latter slidably encircling the

shank 2, adapting said jaw 4 to be adjusted to and from the stationary jaw 1.

Connected firmly with the inner side of the yoke 5 is the tongue 6 which enters the shank 2, the latter being hollow or channeled for the purpose, and permitting said tongue to move with the yoke and consequently with the jaw 4.

The underside of the tongue is tapering forming the inclined plane 7 which acts as a cam and is engaged by the head 8 of the lever 9, the latter being mounted on the shank 2 by the pivot or axis 10, it being noticed that said head 8 and adjacent pivotal portion of the lever enter the channel of the shank and are movable therein, the remainder of said lever in the normal condition of the wrench being outside of said shank, then in closing the jaws a portion of the body of the lever below its pivot is adapted to be moved into the channel or hollow of the handle 3. When said lever is in closed position it may be grasped simultaneously with the handle by hand, thus retaining the jaw 4 in adjusted position closed on the article to be held by the wrench against the stationary jaw.

11 designates a spring whose upper end is attached to the tongue 6, as at 12, and whose lower end is attached to the adjacent end of the handle 3, as at 13, said spring occupying the channel of the shank and serving to return the movable jaw 4 to its normal position, the wrench then being open.

The operation is as follows:—

The jaws of the wrench are open as in Figs. 1 and 2, when the article to be engaged is placed between the same. Then the lever 8 and handle 3 grasped by the hand are pressed together, whereby the head of the lever bears against the inclined plane 7 of the tongue 6 and rides downwardly thereon thus elevating said tongue and consequently the yoke 5 and movable jaw 4 pressing the latter firmly against the article placed between the jaws and so clamping said article when the wrench may be operated as usual.

When the lever 9 is let go, the spring 11 draws down the tongue and consequently the yoke and stationary jaw, the wrench thus being opened whereby it is removable from the article with which it was engaged, the lever 9 having resumed its normal position.

The stationary jaw 1, shank 2 and handle 3 are formed of a piece of suitable metal or material bent longitudinally on itself form-

ing said members hollow or channeled so that said shank is adapted to receive the tongue 6, portions of the lever 9 and portions of the spring 11 respectively. As the 5 stationary jaw is channeled in order to strengthen the same there is placed therein between the sides thereof the filling piece 14 of rigid metal or material shaped to conform to said jaw and connected with the 10 same by the rivets 15.

The lever 9 is formed of a piece of suitable metal or material bent on itself and its sides swaged together forming said lever of increased strength, the bend of the piece being swelled forming the flange 16 which provides a broad surface for the fingers of the hand in grasping the lever to press it toward the handle 3 in closing the jaws of the wrench.

20 Having thus described my invention what I claim as new and desire to secure by Letters Patent, is:—

1. A wrench comprising a stationary jaw, a shank carrying the same, a handle for said shank, a sleeve slidable on said shank, a movable jaw, the same being connected with said sleeve, a tongue attachable to said sleeve adapted to movably engage said shank, said tongue having its lower portion inclined, 25 and a lever mounted on said shank movable to and from said handle, the head of said lever being adapted to engage the inclined portion of said tongue and ride thereon whereby the tongue and sleeve and thereby 30 the movable jaw may be operated to close the jaws.

2. A wrench comprising a stationary jaw, a shank carrying the same, a handle for said shank, a sleeve slidable on said shank, a movable jaw, the same being connected with said sleeve, a tongue attachable to said sleeve adapted to movably engage said shank, said tongue having its lower portion inclined, a lever mounted on said shank 45 movable to and from said handle, the head of said lever being adapted to engage the inclined portion of said tongue and ride thereon whereby the tongue and sleeve and thereby the movable jaw may be operated to close 50 the jaws, and a resilient member connected with the movable jaw and the handle adapted to return the movable parts of the wrench to normal positions.

3. A wrench comprising stationary and movable jaws, a shank, a handle for the latter, a lever on the handle having its head within said shank, and a tongue attached to the movable jaw adapted to carry the latter and to be engaged by said head. 55

4. In a wrench, a stationary jaw, a movable jaw, a shank adapted to carry said stationary jaw, a tongue mounted freely within the shank and adapted to carry said movable jaw, and a lever mounted on said shank adapted to engage said tongue and operate 60 the movable jaw, said lever being formed of a piece bent on itself forming two parallel lengths side by side, the bend of said pieces being outturned forming a laterally 65 extending flange. 70

5. A wrench formed of a stationary jaw, a shank, a movable jaw on the latter, a lever mounted on said shank adapted to operate said movable jaw, a handle on said shank, said jaw, shank and handle being formed of 75 a continuous piece of material channeled throughout its length, a member of the movable jaw being adapted to freely occupy the channel of said shank, the head of said lever being adapted to freely occupy the channel 80 of the shank and the body of said lever being adapted to freely enter the channel in said handle. 85

6. In a wrench, a stationary jaw, a shank adapted to carry the same, a handle on said shank, a movable jaw, a yoke carrying the latter and slidably on the exterior of said shank, a tongue connected with said movable jaw, and movable on the interior of said shank, and a lever on the handle having its 90 head within said shank, engageable with said tongue, whereby the movable jaw may be operated to close the same. 95

7. In a wrench, a channeled shank, a movable jaw mounted thereon, a lever having its head mounted in the channel of said shank and engageable with said jaw, said lever being formed of a piece of material doubled on itself, the bend thereof being outturned laterally forming a laterally extending 100 flange on the forward side of said lever.

FRITZ KETTLER.
